UNITED STATES PATENT OFFICE

95,090

DESIGN FOR A COMBINATION HYPODERMIC NEEDLE AND HUB

Anthony J. Son, Mattapan, Mass., assignor to
MacGregor Instrument Company, Needham,
Mass., a corporation of Massachusetts

Application August 23, 1934, Serial No. 53,029

Term of patent 14 years

To all whom it may concern:

Be it known that I, Anthony J. Son, a citizen of the United States, residing at Mattapan, in the county of Suffolk, Commonwealth of Massachusetts, have invented a new, original, and ornamental Design for a Combination Hypodermic Needle and Hub, of which the following is a specification, reference being had to the accompanying drawing, forming part thereof.

Fig. 1 is a view of one end of a combination

hypodermic needle and hub in accordance with my new design.

Fig. 2 is an edge view of the same.

Fig. 3 is a view of the other edge, and

Fig. 4 is an end view opposite to that of Fig. 1.

I claim:

The ornamental design for a combination hypodermic needle and hub as shown.

ANTHONY J. SON.
